ELECTRICAL FITTING

Karl Schilling, Schwetzingen, near Mannheim,
Germany, assignor to Stotz Kontakt G. m. b. H.,
Mannheim-Neckarau, Germany

Application October 23, 1935, Serial No. 46,275
In Germany November 1, 1934

7 Claims. (Cl. 247—28)

This invention relates to electric attachments or fittings, and especially to current take-off devices.

It is customary to so construct such devices that, by means of a plug inserted into a plug-box sunk into the ground, several current-using devices can be connected at one and the same time directly to the end of one power-line in the sunken receptacle. However, such constructions involve the connection of each current-user directly to the main or supply cable, or to a cumbersome, intermediate coupling, the use of which is usually necessary in order to effectuate multiple distribution or branching of the current. Moreover, they are quite incapable of use out in the open or elsewhere they may be subjected to the action of the elements,—water, wind, air or fire, or sunheat,—and have hence been usable only indoors, as in dwelling rooms, factories, and the like.

It is one of the chief objects of the present invention to provide a large, heavy-duty current take-off device which, withal, will not be cumbersome or have this complex, delicate construction and will be quickly transportable and connectible and disconnectible; and which will be quite well adapted for duty in the open, remaining out-doors exposed to all the elements, yet will never jam or become inoperative due to deterioration caused by exposure and weathering.

The other objects and advantages of the present invention will be made manifest as the construction, and rule of action of the invention are set forth hereinafter.

The presently-preferred embodiment of the invention is shown by way of example in the accompanying drawing, but it is to be understood that the invention is limited in its execution only by the scope of the subjoined claims. In the drawing.

Fig. 1 is a vertical, broken section, partly in elevation, of the assembly, and

Fig. 2 is a section of another part of the invention.

The structure shown in the drawing comprises a two-part casing, *a*, *b*, adapted to be sunk in the ground. In this casing there is rotatably mounted a switch-like part *c*, pressed by coil springs *d* against a flange *e* of the casing-half *a*. In the group *c* is an insulation-member *f*, having plug-bushings *g* closed at the bottom. The lower part of the member *f* is formed as a switch-member cooperating with a complementary stationary switch-part *h*.

In the main casing (*a*, *b*) there is provided a connecting terminal, or binding post, *i*, the upper end of which is segregated from the rest of the article by a separate cover *j* forming a connection-making space, *k*. In this space, the underground lead-in cable, not shown, comes in through the ground, ends there, and is bound to the post. From the post *i*, circuit wires *m* lead to switch contacts *n*.

The member *b* is of a totally impervious material, imperviously joined to part *a*, and defining a space *n* which is therefore rendered completely and permanently watertight and never admits any moisture from outside.

The member *a* is formed with annular projections *o* adapted to lie over complementary annular flanges or projections *r* on the central member *p* when inserted and rotated slightly, acting in the manner of a bayonet joint, whereby the central member or carrier is secured against unwanted removal.

The bottom part of the carrier *p*, is formed as a skirt or pipe-socket *2*, which projects over the plug pins *t* and protects them from damage. There is also provided, in the switching part *c*, an approximately annular collar *3*, which projects over the plug bushings *g*. The members *2* and *3* serve for reciprocally guiding each other; the collar *3* serves additionally to protect the plug bushings *g* from any water which may tend to flow in.

The carrier *p* is filled radially with a mass of insulation, *s*, into which plug pins *t* are set. From these, cables *u* run in a pipe *v* to the top *w* of the carrier *p*. This top has a cap in the form of a handle giving the whole somewhat of a T-shape. The handle is adapted to be seized in inserting the plug and in switching on. The head opens downwardly, and a plurality of current lead-off devices, *x*, in the form preferably of screw or snap receptacles or sockets, are arranged around the interior periphery thereof, as shown, and each is adapted to receive an inserted plug on the end of a cable to the current-consuming device. By this arrangement, though it constitutes also a convenient handle, etc., the joint is absolutely protected from rain, snow, dirt, etc.

When the system is not in use and the carrier is hence detached and lying in storage, the ground-receptacle is adapted to receive a cover *y*, having a locking device *z* of the bayonet-joint type, so constructed and arranged that when the cover *y* is set down onto the plug receptacle and slightly turned, it is secured against removal.

As an additional precaution, if desired, means are provided for receiving an ordinary tumbler-lock operated by a key to prevent unauthorized use of the current supply.

5 In using the article and the system, receptacles *a*, *b*, are located at all desired points in an assembly-field, street square, city-section, an assembly hall, or the like. When not in use, they are rendered inaccessible by means of the double-
10 locked cover *y*. When current is to be taken off, the cover is removed and the carrier *p* in the top part is inserted into the plug-receptacle. This brings the circuit-connectors *g* and *t* together, whereupon the carrier *p* is rotated to
15 lock it, simultaneously closing the switch *h*. The usual cables having a plug-fixture on one end and a current-consumer on the other, are inserted by their plug-end into the sockets *x*.

If desired, an ammeter can be arranged in
20 shunt in either the casing *a*, *b*, or the carrier *p*, to ascertain, at this end, the true current consumption. The casing parts, *a*, *b*, can conveniently be made of stainless iron or ceramics, and artificial insulating materials. The top part *w*,
25 and part *g*, of the carrier can well be made of cast iron, and the part *v* of seamless, drawn-pipe. If desired, however, the whole article can be made in one piece, of an artificial composition-material, or of a ceramic material.

30 I claim:

1. Electrical distribution device comprising a covered housing adapted to be sunk into the ground to be flush therewith and containing water-tight enclosed terminals for connection
35 with a ground cable, a switch electrically connected with said terminals and having its contacts water-tight enclosed in said housing, electrical coupling elements connected with said switch, a clutch member mechanically connected
40 with the actuating member of said switch, a movable plug-like adapter composed of a tube having an insulating body in its lower end, electrical coupling elements mounted on said body and engageable with the aforesaid coupling elements
45 of said housing, a laterally expanded hollow head closing the other end of said tube, a plurality of sockets arranged in said head, conductors within said tube connecting said sockets with the coupling elements of the adapter, a clutch member
50 on the adapter engageable with the clutch member in said housing, and means for interlocking said adapter and said housing whereby said switch is simultaneously actuated to close the circuit.

55 2. Electrical distribution device comprising a covered housing adapted to be sunk into the ground to be flush therewith and containing water-tight enclosed terminals for connection with a ground cable, a switch electrically connected with said terminals and having its contacts water-tight enclosed in said housing, an insulation member, contact sockets mounted on said insulation member and connected with the contacts of said switch, an annular recess surrounding said insulation member, a movable plug-like adapter composed of a tube having an insulating body in its lower end, plug pins engageable with the aforesaid contact sockets of
60 said housing, an apron formed by said tube surrounding said plug pins and disposed to intrude the aforesaid annular recess, a laterally expanded hollow head closing the other end of said tube, a plurality of sockets arranged in said head and electrically connected with said plug pins, a device for locking said adapter in said housing and

means interconnected with said locking device for actuating said switch to close the circuit in dependency from the function of said locking device.

3. Electrical distribution device comprising a 5 covered housing adapted to be sunk into the ground to be flush therewith and containing water-tight enclosed terminals for connection with a ground cable, a switch electrically connected with said terminals and having its contacts water-tight enclosed in said housing, an insulation member forming part of the actuating member of said switch, contact sockets mounted on said insulation member and connected with the contacts of said switch, an annular collar 10 concentrically surrounding and fixed to said insulation member, said collar projecting toward the opening of said housing and forming an annular recess between itself and said insulation member, a lateral projection on said collar forming a clutch member, a locking device forming part of said housing, a movable plug-like adapter composed of a tube having an insulating body in its lower end, plug pins engageable with the aforesaid contact sockets of said housing, an 15 apron formed by said tube surrounding said plug pins and disposed to intrude the aforesaid annular recess, an annular flange fixed to said tube and interlockable with said housing locking device and having a clutch member engageable with the aforesaid clutch member of the housing, a 20 laterally expanded hollow head closing the other end of said tube, a plurality of sockets arranged in said head and electrically connected with said plug pins, said switch being actuated to close the 25 circuit by the interlocking of said clutch member.

4. An enclosed receptacle for installation in the ground to be flush therewith, adapted to receive a movable plug-like adapter to be introduced in vertical direction, comprising a housing 40 having three compartments, one having an inlet for a ground cable and containing terminals for the connection of said cable and a separate water-tight cover for said compartment, the second of said compartments containing a switch, a 45 separate rotatable cover forming the actuating member of said switch, an insulation member, electrical coupling elements engageable with said plug-like adapter and being mounted on said insulation member and connected with the contacts of said switch, the third of said compartments having an open-air outlet designed to receive a removable cover and containing means for mechanically coupling said rotatable cover with said plug-like adapter, the said three compartments being accessible only through said open-air outlet.

5. A water-tight enclosed plug-like adapter for insertion into a receptacle installed on the ground comprising an insulating body, plug pins 50 on said body, a tube containing in one of its ends said insulating body and having a length so as to rise a considerable distance above ground, a laterally expanded hollow head closing the other end of said tube, a plurality of sockets situated 55 on the bottom side of said head and having downwardly inclined socket openings so as to be protected against rain by the upper part of said head and conductors within said tube connecting said plurality of sockets with said plug pins.

6. A water-tight enclosed T-shaped adapter for insertion into a receptacle installed on the ground, comprising an insulating body, plug pins 60 on said body, a tube containing in one of its ends said insulating body and having a length so as 65

to rise a considerable distance above ground, a laterally expanded hollow head forming the crossbar of the T and closing the other end of said tube, a plurality of sockets situated on the bottom side of said head and having downwardly inclined socket openings so as to be protected against rain by the upper part of said head and conductors within said tube connecting said plurality of sockets with said plug pins, rotatable means for locking said adapter in the ground receptacle, the head of said adapter forming a handle for rotating the adapter.

5. Electrical coupling device comprising a stationary and a movable member, said stationary member containing a separate water-tight compartment, terminals within said compartment for

10 the connection of a ground cable, a second, separate water-tight compartment, a switch within said second compartment connected with said terminals, electrical coupling elements connected with said switch, said movable member containing an insulating body, electrical coupling elements on said body engageable with the aforesaid coupling elements, a plurality of sockets adapted to receive each a separate plug, said sockets being spaced a considerable distance 10 apart from said insulating body and mechanically connected therewith by a support, conductors within said support connecting said sockets and said coupling elements on said insulating body.
